UNITED STATES PATENT OFFICE

2,604,071

DROP HAMMER OF THE GRAVITY TYPE

Paul A. Rickrode, Chambersburg, Pa., assignor to Chambersburg Engineering Company, Chambersburg, Pa., a corporation of Pennsylvania

Application April 7, 1950, Serial No. 154,508

14 Claims. (Cl. 121—12)

1

This invention relates to new and useful improvements in drop hammers and more particularly to drop hammers of the gravity type wherein the ram is raised by air or other elastic fluid under pressure.

In drop hammers of this type a forging may require, for example, twelve to fifteen blows of the ram in order properly to shape the metal. However, in most cases the full stroke of the ram is needed for only the first several blows upon the work and the remaining blows required to properly shape the forging usually can be of a stroke substantially less than the full stroke of the ram. The use of a shorter ram stroke, after the first few full stroke blows upon the work, would conserve the power required to operate the hammer and also substantially reduce the wear on the dies. However, prior to the present invention, no practical means have been available for changing the stroke of the ram while the drop hammer is in operation.

With the foregoing in mind, the principal object of the present invention is to provide a drop hammer of the type described having novel mechanical means operable at will to effectively shorten the stroke of the ram during continued operation of the drop hammer.

Another object of the invention is to provide a fluid operated drop hammer of the stated character having novel valve control means operable to shut-off the supply of pressure fluid to the ram lift piston at a predetermined point in advance of the full elevated position thereof so that upward movement of the ram is arrested at a point below the full elevated position of the ram thereby affording a shorter drop stroke for the ram.

A further object of the invention is to provide a pressure fluid operated drop hammer having the operational and structural features and characteristics set forth which is economical and efficient in use and entirely foolproof and safe in operation.

These and other objects of the invention and the various features and details of the construction and operation thereof are hereinafter fully set forth and described with reference to the accompanying drawings, in which:

Fig. 1 is a fragmentary front elevational view partially in section, of a pressure fluid operated drop hammer embodying the present invention;

Fig. 2 is an enlarged fragmentary face view of a valve control lever incorporated in the drop hammer and showing the present invention in operative position;

Fig. 3 is a view similar to Fig. 2 showing the device of the present invention in inoperative position;

Fig. 4 is a fragmentary sectional view in reduced size on line 4—4, Fig. 2;

Fig. 5 is an enlarged fragmentary side elevational view showing the device of the present invention;

Fig. 6 is a sectional view taken on line 6—6, Fig. 5;

Fig. 7 is a sectional view taken on line 7—7, Fig. 5;

Fig. 8 is a perspective view, partially in section, of an adjustable dog which forms a part of the device of the present invention;

Fig. 9 is a detached view in perspective of a sleeve member which is cooperable with the adjustable dog shown in Fig. 8 to position the latter operatively or inoperatively as desired; and

Fig. 10 is a side elevational view showing the control means for the drop hammer in the device of the present invention.

Referring now to the drawings and more particularly to Fig. 1 thereof, the present invention

is shown in conjunction with a fluid pressure operated drop hammer comprising the usual base 1, relatively spaced apart side frames 2 and a head or upper housing 3 which mounts a vertically ranged cylinder for containing a piston 5.

Piston rod 6 has its upper end connected to the piston 5 and its other end is connected to a ram 7 which is mounted for vertical reciprocatory movement between the side frames 2 and adapted, when dropped, to cooperatively engage the usual anvil 8 supported upon the base 1 of the apparatus.

In accordance with the practice usually employed in pressure fluid operated drop hammers, the ram 7 is adapted to drop freely by gravity from the elevated position shown in Fig. 1 downwardly into impact engagement with the anvil 8, and pressure fluid admitted to the cylinder 4 below the piston 5 is utilized to return or raise the latter and ram 7 to the elevated position after each drop.

The elastic pressure fluid utilized to actuate the ram lift piston 5 is under the control of a main valve 10. The valve 10 comprises a cylindrical sleeve member 11 which is mounted horizontally in the head or upper housing 3 of the machine and has a valve element 12 slidable therein. Formed in the housing 3 and surrounding the valve sleeve 11 in axially spaced relation thereto are manifolds 13 and 14 respectively, the former being arranged to receive pressure fluid from a

fluid supply while the latter is in open communication with the lower end of the lift cylinder 4 through a passage 16.

Communication from the fluid pressure manifold 14 to the interior of the valve 12 is provided by ports 17 in the sleeve 11, while communication from the valve element to the cylinder manifold 13 is provided by other ports 18 in said sleeve. The inner end of the valve sleeve 11 is in open communication with an exhaust port 19 provided in the housing 3 and opening to the atmosphere at the rear of the drop hammer.

Actuation of the valve element 12 is effected by means of a control lever 22 disposed for actuation by the ram 7 and suitably connected to a valve rod 23. The control lever 22, constructed as shown in the drawings, is pivotally mounted intermediate its ends upon a pin 24 secured to one of the side frames 2 of the machine. Adjustably secured to the control lever 22 are dogs 25 and 26, respectively, which are arranged to be engaged by the ram 7 in the manner and sequence hereinafter set forth.

The upper end of the lever 22 is pivotally connected to the inner end of a link 27 which has its outer end pivotally connected to an arm 28 fixed on a pin 29 mounted in the side frame 2 and having an arm 29a fixed on its other end. The arm 29a, in turn, is pivotally connected to the lower end of a vertically extending rod 30, the upper end of which is connected to one arm of a bell crank 30a which has its other arm pivotally connected to the aforesaid actuating rod 23 of the valve element.

The construction and arrangement of the lever 22 and the connections therefrom to the valve rod 23 are such that upon engagement of the lowermost dog 25 by the ram 7 during descent thereof, the lever 22 is actuated in the counterclockwise direction with respect to Fig. 1 to thereby cause the valve element 12 to be shifted to the left from the position shown and establish communication through the valve from the manifold 13 to the manifold 14 so that pressure fluid is admitted to the lift cylinder 4 causing the piston 5 and arm 7 to be actuated upwardly. Following this, and in normal operation of the drop hammer, upon engagement of the upper dog 26 by the ram 7 during its upward movement, the lever 22 is actuated in the clockwise direction resulting in shifting of the valve 12 back into the position shown, thus interrupting flow of pressure fluid to the cylinder 4 and exhausting fluid previously admitted to said cylinder to the atmosphere through the exhaust port 19.

A suitable elastic fluid under pressure is supplied to the main valve 10 from a main pressure fluid supply line 31. A part of this fluid is to flow through a pipe 31a, control valve 33 and pipe 32 to a clamp release cylinder (not shown) which may be, for example, of the construction and operation shown and described in the copending application of Alcorn and Weyer, Serial No. 701,942, filed October 8, 1946, now abandoned. The valve 33 has an operating lever 33a which is actuated by a treadle 34 which, when depressed, actuates the valve 33 to admit pressure fluid to the pipe 32 resulting in actuation of such clamp release mechanism to allow the ram 7 to drop.

As previously stated, the full stroke of the ram 7 as controlled by the dogs 25 and 26 on the lever 22 in most cases is necessary only for the first few strokes of a forging operation and for the remaining blows of the ram the length of the stroke may be reduced or shortened to thereby conserve

power required to operate the drop hammer and also reduce wear on the dies. With this in mind, according to the present invention there is provided on the control lever 22 between dogs 25 and 26 thereof, an adjustable dog mechanism which may be projected into the path of the ram for engagement thereby to close the valve 10 and arrest upward movement of the ram 7 at a point substantially below the upper limit of its normal stroke so that the length of the succeeding drop stroke of the ram is materially shortened or reduced in length.

To this end there is pivotally mounted upon the control lever 22 a movable dog member 35. As shown in Fig. 8 of the drawings, the dog 35 has an opening 36 to receive therethrough the control lever 22 and at opposite sides of said opening 36 the dog is provided with upwardly extending spaced parallel arm portions 37 having openings 38 therethrough for reception of a pin 39 by means of which the dog 35 is pivotally mounted on the control lever 22. With reference to Fig. 7, it is to be noted that the opening 36 through the dog member 35 is of greater extent than the width of the control lever 22 in order to permit limited pivotal or swinging movement of the dog 35 with respect to the control lever 22.

Surrounding and slidable with respect to the lever 22 and the arm portions 37 of the dog 35 is the sleeve portion 40 of a control member 41 having also a vertically extending cylinder portion 42 laterally adjacent one side of the said sleeve portion 40. The construction and arrangement of the sleeve portion 40 of the control member 41 is such that when said sleeve 40 is in the lower position resting upon the dog 35, the latter is disposed so that the nose 43 thereof is projected into the path of the ram 7 for engagement thereby during its upward movement as shown in Fig. 2 of the drawings. On the other hand, when the sleeve 40 is raised with respect to the dog 35 a sufficient distance, the over-balance imparted to the dog by the heavier nose portion 43 thereof, as well as the eccentric pivotal mounting of the dog on the lever 22, causes the dog 35 to pivot automatically in the counterclockwise direction to an extent limited by the length of the opening 36 therein thus removing the nose portion 43 from the path of the ram 7 so that the dog 35 is not engaged by the ram during its upward movement.

Actuation of the control member 41 with respect to the lever 22 and dog 35 is accomplished by means of a pressure fluid operated piston 44 which is disposed within the cylinder portion 42 of the member 41 (for example as shown in Fig. 6 of the drawings). The piston 44 is provided with a piston rod 45 which extends through the upper end of the cylinder portion 42 and the free end of said rod 45 has an adjustable threaded connection with a bracket 46 that in turn is pivotally mounted upon a pin 47 carried by the lever 22. A lock nut 48 is provided on the piston rod 45 to secure the threaded connection of the rod 45 to the bracket 46 in the desired position of adjustment.

A coil spring 49 surrounds the piston rod 45 in the cylinder 42 and since the piston rod 45 has its upper end fixedly connected to the lever 22, this spring 49 acts normally to maintain the said cylinder in the raised position with respect to the piston 44 (see Fig. 6) and likewise the sleeve portion 40 in the raised position with respect to the lever 22 and dog 35 with the result that the said dog 35 normally will be disposed in the out-

ward position shown in Figs. 3 and 7 with its nose portion 43 removed from the path of travel of the ram 7. On the other hand, when fluid under sufficient pressure is admitted to the cylinder 42 below the piston 44, the latter remains stationary by reason of its fixed connection to the lever 22 and hence the cylinder 42 and its associated sleeve portion 40 are actuated downwardly against the force of spring 49 with respect to the dog 35 thereby actuating the latter in the clockwise direction to position the nose portion 43 thereof into the path of upward movement of the ram 7. In this connection, it will be noted with respect to Figs. 7 and 8 of the drawings that there is provided adjacent the lower outer ends of the arm portions 37 of the dog 35 inclined cams 37a disposed for engagement by the lower edge of the sleeve 40 upon downward actuation of the latter so that the dog 35 is actuated in the clockwise direction by a cam action. In addition, there is provided inwardly of the nose portion 43 of the dog 35 a recess 43a which is configurated according to the shape of the corresponding or complementary portion 40a of the sleeve 40 so that the latter is received in the dog recess 43a in the relation shown in Fig. 2 of the drawings when the sleeve 40 is in its lowered position and the dog 35 is in the projected or clockwise position.

Pressure fluid is supplied to the cylinder 42 beneath the piston 44 to raise the latter against spring 49 by a pipe system 50, including a flexible portion 50a, which is connected at one end to the cylinder portion 42 as indicated at 51 and has its other end connected to the outlet of a two-way valve 52 having an exhaust 53 opening to the atmosphere and an inlet 54 connected by a flexible hose 55 to the main pressure fluid supply line. In the present instance the valve 52 is operated by a spring mounted plunger 56 and the construction and arrangement of the valve 52 is such that when the plunger 56 is depressed, the valve is actuated to open the valve and cause pressure fluid to flow from the connection 55 through the pipe line 50 to the cylinder 42, thus admitting fluid beneath the piston 44 therein. On the other hand, when the operating plunger 56 is released, the valve 52 is closed and communication is established from the pipe line 50 to the exhaust port 53 so that air in the cylinder 42 is exhausted to the atmosphere.

In the illustrated embodiment of the present invention the valve 52 is mounted at the underside of the main operating treadle 34 of the machine and the valve plunger 56 projects upwardly through an opening 57 in the treadle as shown in Figs. 1 and 10 of the drawings. By this arrangement the operator of the hammer, simply by changing the position of his foot on the treadle 34 is able to establish pressure fluid flow solely to the clamp release mechanism of the machine or simultaneously to both the said release mechanism and the adjustable dog control member 41 at will as may be desired.

In a typical forging operation of the drop hammer embodying the present invention, the operator can make the first few blows of the operation with the ram operating through its full stroke simply by depressing the main foot treadle 34 of the machine and the remaining blows of the operation can be carried out by a shorter stroke of the ram 7 simply by the operator shifting his foot on the treadle 34 so that in the act of depressing the latter the operator also depresses the plunger 56 to open valve 52 and thereby admit pressure fluid to the cylinder 42

causing the dog 35 to be projected into the path of the ram 7, thus causing the ram to operate through a stroke of substantially reduced length.

While a particular embodiment of the present invention has been illustrated and described herein, it is not intended to limit the invention to such disclosures, and changes and modifications may be incorporated and embodied therein within the scope of the following claims.

10 I claim:

1. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a member carried by said lever normally positioned out of the path of travel of the ram and actuatable into the path of travel of the ram for engagement thereby on the upward stroke of the ram to close the valve, and means to actuate said member into the path of the ram.

2. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a first projection on said lever engageable by the ram on the drop stroke thereof to actuate the lever and open the valve to admit pressure fluid to said piston to raise the ram, a second projection on the lever engageable by the ram on the upward stroke thereof to close the valve and prevent admission of fluid to the lift piston, a member carried by said lever intermediate said first and second projections normally positioned out of the path of travel of the ram and actuatable into the path of travel of the ram for engagement thereby on the upward stroke of the ram to close the valve and establish a shorter working stroke for the ram, and mechanism to actuate the member into the path of the ram.

3. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a member carried by said lever normally positioned out of the path of travel of the ram and actuatable into the path of travel of the ram for engagement thereby on the upward stroke of the ram to close the valve, and control means cooperable with said member including a pressure fluid operated piston operable to actuate said control means and in turn the member to project the latter into the path of the ram.

4. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a member carried by said lever normally positioned out of the path of travel of the ram and actuatable into the path of travel of the ram for engagement thereby on the upward stroke of the ram to close the valve, control means cooperable with said member including a pressure fluid operated piston operable to actuate said control means and in turn the mem-

ber to project the latter into the path of the ram, and valve means operable by the operator at will to admit pressure fluid to said piston.

5. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a member carried by said lever normally positionable out of the path of travel of the ram and actuatable into the path of the ram for engagement thereby on the upward stroke of the ram to close the valve, control means cooperable with said member and actuatable in one direction to actuate said member and project the latter into the path of the ram, means urging said control means in the opposite direction so that the member normally is positioned out of the path of travel of the ram, and means operable to actuate the control means in said one direction to position the member in the path of travel of the ram.

6. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a member carried by said lever normally positionable out of the path of travel of the ram and actuatable into the path of the ram for engagement thereby on the upward stroke of the ram to close the valve, control means cooperable with said member and actuatable in one direction to actuate said member and project the latter into the path of the ram, means urging said control means in the opposite direction so that the member normally is positioned out of the path of travel of the ram, and a pressure fluid operated piston in said control means operable to actuate the latter in said one direction and position the member in the path of travel of the ram.

7. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a member carried by said lever normally positionable out of the path of travel of the ram and actuatable into the path of the ram for engagement thereby on the upward stroke of the ram to close the valve, control means cooperable with said member and actuatable in one direction to actuate said member and project the latter into the path of the ram, means urging said control means in the opposite direction so that the member normally is positioned out of the path of travel of the ram, a pressure fluid operated piston operable to actuate said control means in said one direction and position the member in the path of travel of the ram, and valve means operable by the operator at will to admit pressure fluid to said piston.

8. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a first projection on said lever engageable by the ram on the drop stroke thereof to actuate the lever and open the valve

to admit pressure fluid to said piston to raise the ram, a second projection on the lever engageable by the ram on the upward stroke thereof to close the valve and prevent admission of fluid to the lift piston, a member carried by said lever intermediate said first and second projections normally positioned out of the path of travel of the ram and actuatable into the path of travel of the ram for engagement thereby on the upward stroke of the ram to close the valve and establish a shorter working stroke for the ram, and control means cooperable with said member including a pressure fluid operated piston operable to actuate said control means and in turn the member to project the latter into the path of the ram.

9. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a first projection on said lever engageable by the ram on the drop stroke thereof to actuate the lever and open the valve to admit pressure fluid to said piston to raise the ram, a second projection on the lever engageable by the ram on the upward stroke thereof to close the valve and prevent admission of the fluid to the lift piston, a member carried by said lever intermediate said first and second projections normally positioned out of the path of travel of the ram and actuatable into the path of travel of the ram for engagement thereby on the upward stroke of the ram to close the valve and establish a shorter working stroke for the ram, control means cooperable with said member including a pressure fluid operated piston operable to actuate said control means and in turn the member to project the latter into the path of the ram, and valve means operable by the operator at will to admit pressure fluid to said piston.

10. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a dog member pivotally carried by said lever and overbalanced so that it is normally positioned out of the path of travel of the ram and actuatable into the path of travel of the ram for engagement thereby on the upward stroke of the ram to close the valve, and control means cooperable with said dog member and actuatable in one direction to actuate the dog member to project the latter into the path of the ram.

11. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a first projection on said lever engageable by the ram on the drop stroke thereof to actuate the lever and open the valve to admit pressure fluid to said piston to raise the ram, a second projection on the lever engageable by the ram on the upward stroke thereof to close the valve and prevent admission of fluid to the lift piston, a dog member pivotally carried by said lever intermediate said first and second projections and overbalanced so that it is normally positioned out of the path of travel of the ram and actuatable into the path of travel of the ram for engagement thereby on the upward stroke of

the ram to close the valve and establish a shorter working stroke for the ram, control means actuatable in one direction to project the dog member into the path of the ram, and spring means urging said control means in the opposite direction so that the dog member normally is positioned out of the path of the ram.

12. In a drop hammer having a ram adapted to drop freely by gravity and having a pressure fluid operated piston for raising the ram, a pressure fluid system including a valve to control the flow of pressure fluid to and from said piston, a pivoted control lever operatively connected to said valve for actuating the same, a dog member pivotally carried by said lever and overbalanced so that it is normally positioned out of the path of travel of the ram and actuatable into the path of travel of the ram for engagement thereby on the upward stroke of the ram to close the valve and establish a shorter working stroke for the ram, control means slidably surrounding and operable with said lever and dog member operable in one direction to actuate said control means and in turn the dog member to project the latter into the path of the ram, and spring means urging the control means in the opposite direction so that the dog member normally is positioned out of the path of the ram.

13. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a dog member pivotally carried by said lever intermediate said first and second projections and overbalanced so that it is normally positioned out of the path of travel of the ram and actuatable into the path of travel of the ram for engagement thereby on the upward stroke of the ram to close the valve and establish a shorter working stroke for the ram, control means cooperable with said member and actuatable in one direction to actuate said member and project the latter into the path of the ram, means urging the control means in the opposite direction so that the member normally is positioned out of the path of travel of the ram, a pressure fluid operated piston in said control means operable to actuate the latter in said one direction and position the member in the path of travel of the ram, and valve means operable by the operator at will to admit pressure fluid to said piston.

14. In a drop hammer having a ram adapted to drop freely by gravity and having a pressure fluid operated piston for raising the ram, a pressure fluid system including a valve to control the flow of pressure fluid to and from said piston, a pivoted lever operatively connected to said valve for actuating the same, a first projection on said lever engageable by the ram on the drop stroke thereof to actuate the lever and open the valve to admit pressure fluid to said piston to raise the ram, a second projection on the lever engageable by the ram on the upward stroke thereof to close the valve and prevent admission of fluid to the lift piston, a dog member pivotally carried by said lever intermediate said first and second projections and overbalanced so that it is normally positioned out of the path of travel of the ram and actuatable into the path of travel of the ram for engagement thereby on the upward stroke of the ram to close the valve and establish a shorter working stroke for the ram, control means cooperable with said member and actuatable in one direction to actuate said member and project the latter into the path of the ram, means urging the control means in the opposite direction so that the member normally is positioned out of the path of travel of the ram, a pressure fluid operated piston in said control means operable to actuate the latter in said one direction and position the member in the path of travel of the ram, and valve means operable by the operator at will to admit pressure fluid to said piston.
